UNITED STATES PATENT OFFICE.

SIDNEY W. STRAUS, OF WASHINGTON, DISTRICT OF COLUMBIA.

DESIGN FOR A DOLL OR STATUETTE.

47,657.

Specification for Design.

Patented July 27, 1915.

Application filed April 27, 1915. Serial No. 24,357. Term of patent 3½ years.

To all whom it may concern:

Be it known that I, SIDNEY W. STRAUS, a citizen of the United States, a resident of the city of Washington, in the District of Columbia, have invented a new, original, and ornamental Design for Dolls or Statuettes, of which the following is a specification, reference being had to the accompanying drawings, forming a part thereof.

Figure 1 is a front view of the design comprising my invention. Fig. 2 is a side view showing the statuette comprising my invention in profile. Fig. 3 is a back view of the said statuette.

The statuette comprising the invention set forth in this application, is the figure of a boy with his elbows turned outwardly at a sharp angle and his hands inserted in the side pockets of his trousers. The legs are bowed and the feet are set together. The face is slightly up-turned and the head is covered with a cap set well on the back thereof. A caddy bag is arranged across the back and is filled with various golf clubs.

Having thus described my invention what I claim is:

The design of a doll or statuette substantially as shown and described.

SIDNEY W. STRAUS.
